SCREW MACHINE

William E. Joyce, William H. Himes, and Delbert I. Wilson, Dayton, Ohio, assignors to The City Engineering Company, Dayton, Ohio, a corporation of Ohio

Application January 12, 1942, Serial No. 426,484

2 Claims. (Cl. 82—28)

This invention relates to a screw machine.

It is an object of the invention to provide a screw machine having an independent variable speed drive for the screw machine cam shaft so as to provide an infinite variety of speeds in order to secure the maximum number of pieces per hour according to the type of piece and the metal from which it is being made.

It is a further object of the invention to provide means of adjusting the speed of the cam shaft while the machine is operating so that the effect of the adjustment on the making of the parts can be observed simultaneously with the adjustment. By this means the adjustment can be effected so that the tool will do the best work which can be determined primarily by observing the machine as it operates. Heretofore in the art it has been necessary to stop the machine and make a complicated series of adjustments in variation of speed by the use of pickoff gears and other similar mechanisms. It was, therefore, impossible to make the adjustment continuously both to increase or decrease speeds while observing the action of the tool on the work. Furthermore, such adjustments to the prior art only permitted fixed variations in speed whereas the subject of the present invention is to provide an infinite variety of speeds in combination with various orienting speeds, depending upon the setting of the adjusting mechanism.

It is a further object of the invention to provide a straight line spindle drive likewise adjustable to an infinite variety of speeds so that the correct combination of speeds for the performance of the particular work desired can be secured by adjusting the speed of the cam shaft and of the spindle to provide a precision adjustment for high production and fine workmanship; and to provide such an adjustment, when once made, which will bring about a combination of speeds of the spindle and cam shaft that the two shafts will be respectively operating in synchronism at their maximum combination efficiency.

It is a further object to provide, in this combination of drives for the spindle and cam shaft, an arrangement by which if the drive shaft drive ceases to operate, then the cam shaft drive will be rendered inoperative stopping the cam shaft and preventing the wrecking of the tools. Heretofore, in the art, there has been no way by which this disadvantage could be overcome except for the operator to shut down the machine which cannot be done quickly enough manually to prevent the wrecking of the tools.

It is a further object of the invention to provide an interconnected electrical supply system whereby when one of the drive motors, such as the main drive motor for the spindle, is overloaded then all of the remaining motors including the drive motor will be disconnected from the power source and by this means a wrecking of the tools is prevented.

It is a further object of the invention to provide a mounting for the motor and change speed mechanism in such a manner on the base casting as to rigidly position, support and align it and to maintain a low center of gravity and to provide in combination therewith a straight line drive shaft mounted in self-aligning bearings on the base casting adjacent the bottom thereof close to the floor to give the maximum rigidity to the alignment of the shaft and the maximum reduction of vibration of gyroscopic movement of the shaft. This also provides a straight line drive with direct power take offs to the spindle and attachment mechanisms at spaced points between the bearings.

It is a further object of this invention to have such an adjustment to the mechanism that you can get fractional number of parts for time interval up to the maximum machine capacity as distinguished from getting even number of parts with the adjusting mechanism of the prior art.

It is a further object of the invention to provide adjusting mechanism for the cam shaft which has a predetermined number of speed adjustments as guides for the operator with an infinite number of adjustments between each guide adjustment and in combination with this infinite variation of adjustment a multiple belt and pulley arrangement providing a large number of speed changes and ratios.

In the drawings:
Figure 1 is an end elevational view of a screw machine having portions thereof in cross-section to show features of this invention.

Figure 2 is a side elevational view of a screw machine having portions thereof broken away to show features of this invention.

Figure 3 is an elevational view of a dial which indicates cam shaft speed.

Figure 4 is an elevational view of a dial indicating spindle speed.

Figure 5 is a cross-sectional view of the drive shaft for the screw machine.

Figure 6 is a schematic wiring diagram of the electrical controls for the screw machine.

In this invention there is provided an independent motor drive with a variable speed drive

associated therewith for the cam shaft and the spindle of the screw machine. The spindle drive is from a motor and change speed mechanism mounted in one end of the base casting driving a straight line drive shaft mounted in self-aligning bearings. This shaft carries the drive pulley for the belt for the spindle. This belt is kept taut by an idler so arranged that when the belt breaks the idler will move to cut the power from the spindle motor stopping the spindle and also stopping the other motors.

The cam shaft drive is through a variable speed mechanism through an independent motor. This mechanism has 13 major stops or positioning points to guide the operator in selecting the speeds, but between each point the variation of speed can be infinite. The drive pulley on the change speed shaft can either drive direct from a small pulley to a large one driving the cam shaft or vice versa, or through a pick off pulley on the side of the base casting giving three separate combinations with each of the 13 stops with an infinite variation of speed between the stops.

The independent adjustment of the two motors for cam shaft and spindle shaft permits of bringing a combined relative speed adjustment in the final adjustment which permits of adjusting the tools to their maximum efficiency depending upon the type of the piece, the nature of the tool and the metal and of doing this while the machine is running.

The screw machine consists of a base casting 10 having a hollow interior 11 for enclosing the drive shaft 12. The base casting 10 has an extended portion 13 within which a variable speed drive unit 14 is positioned.

The variable speed drive unit 14 is directly connected to an electric motor 15 which has a flange 16. The flange 16 is bolted to the extended portion 13 of the base casting 10 by means of suitable bolts 17.

The variable speed drive unit 14 is of any suitable type having infinite changes in its speed range. The variable speed drive unit may be of the hydraulic type or can be a mechanically coupled type of unit. In any instance, however, the variable speed drive unit can have its output shaft varied in speed over a wide range and in an infinite number of steps or gradual changes. A suitable speed adjustment control handle 18 extends from the variable speed drive unit 14 for changing the speed of the output shaft 19.

The output shaft 19 of the variable speed drive unit 14 is connected to the drive shaft 12 by means of a flexible coupling 20. The drive shaft 12 is supported by means of self-aligning bearings 21 and 22, to be hereinafter described, which are positioned within support webs 23 and 24 respectively extending upwardly from the bottom wall 25 of the base casting 10.

The drive shaft 12 carries a drive pulley 26 which is keyed upon the shaft 12 by means of the key 27 and is secured in position by means of the set screw 28.

The base casting 10 supports a frame 29 which carries a headstock 30 having a spindle 31 suitably bearinged therein. The spindle 31 carries a pulley 32 which is engaged by a belt 33 extending thereover. The belt 33 also engages the drive pulley 26, thereby providing means for driving the spindle 31 from the drive shaft 12.

A tool head is supported upon the frame 29 and is adapted to carry a plurality of turning tools. The turning tools carried by the tool head 34 are adapted to engage a work piece carried

by the spindle 31 for turning work of various types.

The turning tools are actuated by means of cams 35 carried upon a cam shaft 36 which is bearinged to the frame 29 by means of the bearings 37 and 38. The surface of the cams 35 is generated to produce the desired motion by the work tool to make a cut upon the work piece of a desired contour.

10 The cam shaft 36 is driven by means of a worm and worm wheel drive contained within the housing 39. The worm is carried upon a shaft 40 which extends from the housing 39. A pulley 41 is carried upon the shaft 40 and has a belt 42 extending thereover into engagement with a pulley 43 carried upon the output shaft 44 of a variable speed drive unit 45 driven by an electric motor 46.

15 The variable speed drive unit 45 and the electric motor 46 are suitably carried upon the base casting 10 by means of a support frame 47. The variable speed drive unit 45 may be of any conventional type wherein the output shaft thereof can have the speed changed in an infinite number of steps or in a gradual change. This variable speed drive unit 45 can be of the same type as the variable speed drive unit 14 for the drive shaft 12. A speed adjustment control handle 48 is provided for the variable speed drive unit 45 for changing the speed of rotation of the output shaft 44.

20 The pulleys 41 and 43 are of the double pulley type so that the range of the variable speed delivery unit 45 can be raised or lowered depending upon the pulley set connected by the belt 42.

25 The cams 35 carried upon the cam shaft 36 are adapted to move the work tools with respect to the work piece upon the spindle 31 through a series of levers 49 and 50. The lever 49 is provided with a cam follower 51 for engaging the surface of the cam 35. The contour of the cam 35 thus controls the movement of the tool with respect to the work piece and the speed of rotation of the cam determines the period of time that the tool will be in or out of engagement with the work piece.

30 Since the cam shaft 36 is driven by means of a variable speed drive unit, the speed of rotation of the cam shaft will be infinitely variable over the range of operation of the variable speed drive unit 45. The drive arrangement of this invention for the cam shaft 36 also provides means whereby the speed of rotation of the cam shaft 36 can be changed while the screw machine is operating. There are no gears or other mechanical equipment to change when the speed of the cam shaft is to be altered, but rather the variable speed drive unit 45 permits an infinite number of speeds of the output shaft 44 thereof throughout its range of operation. Therefore, the speed of operation of the cam shaft can be controlled or changed when the screw machine is operating.

35 An indicating dial 52 is provided on the variable speed drive unit 45 to indicate the range within which the unit is operating. This dial 52 is shown in Figure 3. The face of the dial 52 is provided with indicia thereon and in the instance of this invention the dial face is divided into 13 segments. Each segment represents a range of speeds of operation of the cam shaft. The particular range of the cam shaft drive unit of this invention is from $\frac{1}{4}$ R. P. M. to 20 R. P. M. Since the speed of rotation of the cam shaft 36 determines the number of pieces which are produced upon the screw machine it can readily be seen that the number of pieces produced by the

machine can be varied over a considerable range. The slower the rotation of the cam shaft 36 the fewer the number of pieces produced.

As heretofore disclosed the spindle 31 is driven by means of the variable speed drive unit 14, the drive unit 14 being infinitely variable throughout its entire speed range. Therefore, the spindle 31 of the screw machine is capable of being driven at any speed, dependent only upon the setting of the variable speed drive unit 14. The drive unit of this invention is capable of speed variation from about 680 R. P. M. to 6000 R. P. M. A dial 53 is provided for the variable speed drive unit 14 and has indicia thereon to indicate the range within which the spindle 31 is operating. The indicia merely provides means whereby the operator of the machine can orient the speed of rotation of the spindle within a general speed range. After obtaining the general range the operator can then adjust the variable speed drive unit 14 by means of the handle 18 until the exact rotation desired is obtained.

It is to be understood that the screw machine is preferably operating during the final setting of the speeds of operation of the cam shaft 36 and the spindle 31 so that the operator can inspect the results of operation upon the work piece to determine the most efficient operating point for the particular material being used.

It is well known that in manufacturing processes the quality of raw stock will vary to some extent and if a machine is set to work upon raw stock of a particular quality that it may not be set for the most efficient operation upon raw stock of a slightly different quality. Therefore, this invention provides an apparatus wherein the speeds of operation of the spindle and the cam shaft can be varied individually to alter working conditions slightly to meet the variance in quality of raw stock.

The drive shaft 12 of the screw machine is supported upon the self-aligning bearings 21 and 22. The bearing 21 consists of a self-aligning ball bearing set 54 which is carried upon a bushing 55 pinned to the shaft 12 by means of the pin 56. The inner race 57 of the ball bearing set 54 is retained upon the bushing 55 by means of the nut 58 while the outer race 59 is retained in position by means of a sleeve 60 secured between the cover 61 and the race 59. This assembly is supported within the web 23 which extends upwardly from the bottom wall 25 of the base casting 10, thereby providing a rigid bearing support for the drive shaft 12. Suitable oil seals 62, 63 are provided in the cover 61 and the web 23 to retain lubricant upon the self-aligning ball bearing set 54.

The web 24 extending upwardly from the bottom wall 25 of the base casting 10 carries the second bearing 22 for the drive shaft 12. This bearing is supported by means of a plate 64 which is bolted to the web 24 by means of the bolts 65. A sleeve 66 is positioned within the plate 64 and carries a self-aligning ball bearing set 67 within a recess 68. The inner race 69 of the ball bearing set 67 is supported upon a bushing 70 and is secured in position by means of a nut 71 threaded upon the end of the bushing 70. The outer race 72 is carried by the sleeve 66 and is retained in position by the ring 73. An oil cup 74 is carried by the sleeve 66 for directing lubricant to the self-aligning ball bearing set 67.

As will be seen from Figures 2 and 5, the drive shaft 12 is directly in line with the output shaft 19 of the variable speed drive unit 14. Also, the webs 23 and 24, which carry the self-aligning

bearings 21 and 22, are positioned with the bearings closely adjacent the bottom wall 25 of the base casting 10. The arrangement thus provides a rigid support for the drive shaft 12 to prevent vibration thereof.

A pulley 75 is secured to the end of the drive shaft 12 and has a belt 76 extending thereover into engagement with a pulley 77 positioned upon a combination centering, drilling and tapping attachment 78. The pulley 75 and the belt 76 thus provide means for driving the tools carried by the combination attachment 78. Also, the speed of operation of the tools carried by the attachment 78 are variable over the same range of operation as the spindle 31 since the spindle is driven from the same drive shaft 12.

A pulley set 79 is secured to the drive shaft 12 and is adapted to have a belt associated therewith for driving a slotting mechanism adapted to be attached upon the screw machine. The slotting apparatus is an attachment and is not shown in the present drawings. However, the slotting attachment is driven at a proper speed since the drive pulleys 79 for the same are carried upon the drive shaft 12 which is controlled by the variable speed drive unit 14.

As heretofore described the spindle 31 is driven by means of a belt 33 extending between the pulleys 32 and 26. If the belt 33 should break the spindle 31 would stop rotating, but the cam shaft 36 would continue to rotate to advance the tools upon the tool head 34 into engagement with the now stationary work piece, whereby the tools would be damaged. Therefore, it becomes essential that the cam shaft 36 shall be stopped when the belt 33 should break, or for some other reason should stop driving the spindle 31.

An idler pulley 80 is carried upon a yoke 81 pivoted upon a pin 82 carried upon a bracket 83 secured to the base casting 10. The idler pulley 80 is retained in engagement with the belt 33 by means of a spring 84 which is positioned between the yoke 81 and a stud 85, secured to the base casting 10. The idler pulley 80 thus tensions the belt 33 to maintain the same in the proper taut condition for driving the spindle 31.

The yoke 81 carries a pin 86 which is adapted to engage a plunger 87 of an electric switch 88 secured to the wall of the base casting 10. The pin 86 extends through a slot 89 provided in the base casting wall 10 to engage the yoke 81 to prevent the pin 86 from breaking.

The switch 88 is located in the holding circuit of a starting controller 91. The starting controller 91 (see Figure 6) is provided with a series of blades 92, 93 and 94 for making circuit to the spindle drive motor 15 and the cam shaft drive motor 46. A blade 95 establishes a holding circuit for the solenoid 96 of the controller 91 through the overload relay 97 and the electric switch 88. As long as the switch 88 and the overload 97 are closed the spindle drive motor 15 and the cam shaft drive motor 46 will be supplied with current.

If the belt 33 should break or for some reason leave the idler pulley 80 the yoke 81 will pivot about the pin 82 causing the pin 86 to strike the plunger 87 and open the switch 88. The holding circuit to the solenoid 96 will be broken and the controller 91 will be opened, thereby stopping the spindle drive motor 15 and the cam shaft drive motor 46. Since both motors are stopped instantly, the tools driven by the cam shaft 36 will not be damaged by engagement with a non-rotating work piece.

The overload control 97 is placed in series with the spindle drive motor 15 so that if the motor 15 should become overloaded the overload control 97 will open and thereby stop the spindle drive motor 15 and the cam shaft drive motor 46. This overload control is thus a safety measure for the spindle drive motor 15 and insures stopping of the cam shaft drive motor 46 whenever the spindle motor 15 is halted.

A thermal control having blades 98 and 99 is placed in series with the cam shaft drive motor 46 so that if the motor 46 should overheat the circuit to the motor will be opened and thereby stop the same. A manual start button 100 provides means for initially starting operation of the screw machine.

While the apparatus disclosed and described herein is a preferred form of the invention, yet it is to be understood that mechanical modifications can be made without departing from the spirit of the invention, and that all such modifications as fall within the scope of the appended claims are intended to be included herein.

Having thus fully described our invention what we claim as new and desire to secure by Letters Patent is:

1. A screw machine comprising a base member having a bottom wall, a spindle supported by said base member, a variable speed drive unit and an electric motor for the same supported by said base member and disposed adjacent said bottom wall, an output shaft extending from said variable speed drive unit, support members extending upwardly from said bottom wall, self-aligning bearings carried by said support mem- 35

bers, a drive shaft disposed within said self-aligning bearings and coupled to said output shaft in alignment therewith, pulley means carried by said drive shaft, belt means extending from said pulley means to said spindle for driving the same, an idler pulley in engagement with said belt means, and switch means adapted to be actuated by said idler pulley if said belt means should leave said idler pulley for stopping operation of the screw machine.

2. In a screw machine, a base member having a bottom wall, a spindle supported by said base member, a cam shaft supported adjacent said spindle, a variable speed drive unit and an electric motor for the same supported by said base member, means drivingly connecting said variable speed drive unit to said cam shaft, a second variable speed drive unit and electric motor for the same supported by said base member adjacent said bottom wall, support members extending upwardly from said bottom wall, self-aligning bearing members carried by said support member, a drive shaft disposed within said self-aligning bearings and connected to said second variable speed drive unit, pulley means carried by said drive shaft, belt means extending between said pulley means and said spindle to drive the same, an idler pulley engaging said belt means, and switch means adapted to be actuated by said idler pulley if said belt means should leave said idler pulley to stop said motor for said variable speed drive unit for said cam shaft.

WILLIAM E. JOYCE,
